CLAIM

The ornamental design for an upper handle for photography device, as shown and described.

DESCRIPTION

FIG. 1 is a front view of an upper handle for connecting to a photography device according to the present design; FIG. 2 is a top view of the upper handle for photography device of FIG. 1;

FIG. 3 is a rear view of the upper handle for photography device of FIG. 1;

FIG. 4 is a bottom view of the upper handle for photography device of FIG. 1;

FIG. 5 is a right side view of the upper handle for photography device of FIG. 1;

FIG. 6 is a left side view of the upper handle for photography device of FIG. 1; and,

FIG. 7 is a perspective view of the upper handle for photography device of FIG. 1.

The broken lines in the drawings depict portions of the upper handle for photography device that form no part of the claimed design.
